His Attorney

UNITED STATES PATENT OFFICE.

WILLIAM C. HAYMAN, OF SCHENECTADY, NEW YORK, ASSIGNOR TO GENERAL ELECTRIC COMPANY, A CORPORATION OF NEW YORK.

ELECTRIC CONDUCTOR.

1,267,868.

Specification of Letters Patent. Patented May 28, 1918.

Application filed March 9, 1916. Serial No. 83,056.

To all whom it may concern:

Be it known that I, WILLIAM C. HAYMAN, a citizen of the United States, residing at Schenectady, in the county of Schenectady, 5 State of New York, have invented certain new and useful Improvements in Electric Conductors, of which the following is a specification.

The present invention relates to insulated 10 electric conductors having coverings which are provided with one or more colored marking threads, which thread or threads may be raised or not as found desirable. The invention relates particularly to conductors which 15 are covered on the outside with a braiding. It has heretofore been customary in connection with such conductors to braid a marking thread into the covering by using a dyed thread of distinctive color on one of the bobbins 20 on the braiding machine, such thread being of the same size, or a slightly larger size, than the others, the latter arrangement giving a raised marking thread. With such an arrangement it has been found that the 25 saturating water proofing compound, which is usually black in color, and which is applied after the braiding operation is completed, discolors the marking thread to such an extent that it is often difficult, if not im- 30 possible to distinguish it.

I have discovered that this difficulty can be overcome by utilizing in place of a dyed marking thread, a thread impregnated with a filler which renders the thread impervious 35 to the saturating water proofing compound, as for example, a thread filled with a colored wax or paint, such filler, as the colored wax or paint, being applied to the thread before it is braided. By this arrangement I 40 have found that the saturating compound will not discolor the marking thread.

My invention is applicable to a single conductor intended for use by itself, or to a cable made up of two or more conductors, 45 one or more of which are provided with a marking thread.

The accompanying drawing illustrates a cable embodying my invention, a cable comprising two conductors being shown.

50 Referring to the drawing, 1 and 2 indicate the two conductors of a cable 3. The wire of each conductor may be first suitably covered with one or more layers of insulation, as rubber, after which the braided covering

4 is put on. The conductors may then be 55 suitably twisted together, or laid side by side and covered with a braiding 5 as indicated in the drawing, or formed into a cable in any other suitable manner. In the conductor 2 is a marking thread 6 which, in accordance 60 with my invention, is a thread which prior to braiding has been impregnated with a filler, as a colored wax or paint of suitable composition.

In accordance with the provisions of the 65 patent statutes, I have described the principle of operation of my invention, together with the apparatus which I now consider to represent the best embodiment thereof; but I desire to have it understood that the apparatus shown is only illustrative and that the 70 invention can be carried out by other means.

What I claim as new and desire to secure by Letters Patent of the United States, is:—

1. A conductor having a covering treated 75 with a saturating water proofing compound, said covering comprising a marking thread which previous to being applied to the conductor has been impregnated with a filler of distinctive color which renders the thread 80 impervious to the saturating compound whereby the distinctive coloring of the marking thread will not be obliterated by the saturating compound.

2. The combination in a cable, of a conductor having a covering treated with a saturating water proofing compound, said covering comprising a marking thread which previous to being applied to the conductor has been impregnated with a filler of distinctive color which renders the thread 85 impervious to the saturating compound whereby the distinctive coloring of the marking thread will not be obliterated by the saturating compound.

3. In a cable comprising a plurality of conductors having braided coverings which, after the braided coverings have been applied, is treated with a saturating water proofing compound, a marking thread braided into the covering of one of the conductors, said marking thread, prior to being braided into the covering, having been impregnated with a colored filler which renders the thread 100 impervious to the saturating compound whereby the distinctive coloring of the marking thread will not be obliterated by the saturating compound.

4. In a cable comprising a plurality of conductors having braided coverings which are saturated with a water proofing compound, a marking thread braided into the covering of one of said conductors, which thread is impregnated with paint of a distinctive color, said paint serving to render
- 5

the marking thread impervious to the saturating compound whereby the distinctive coloring of the marking thread will not be 10 obliterated by the saturating compound.

In witness whereof, I have hereunto set my hand this 8th day of March 1916.

WILLIAM C. HAYMAN.
